(57) **CLAIM**

The ornamental design of an intercom control head as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a right, upper, front perspective view of an intercom control head;

FIG. 2 is a right, lower, rear perspective view thereof;

FIG. 3 is a front, elevation view thereof;

FIG. 4 is a back, elevation view thereof;

FIG. 5 is a left, elevation view thereof;

FIG. 6 is a right, elevation view thereof;

FIG. 7 is a top, plan view thereof; and,

FIG. 8 is a bottom, plan view thereof.

The broken lines in the drawings are illustrative of the environment of the claimed design and form no part of the design to be patented.

1 Claim, 8 Drawing Sheets
